UNITED STATES PATENT OFFICE.

JOSEPH H. MURRAY, OF HOMER, GEORGIA.

MAIL-BAG-CATCHING APPARATUS.

1,279,408.

Specification of Letters Patent. Patented Sept. 17, 1918.

Application filed August 10, 1917. Serial No. 185,549.

To all whom it may concern:

Be it known that I, JOSEPH H. MURRAY, a citizen of the United States, residing at Homer, in the county of Banks and State of Georgia, have invented new and useful Improvements in Mail-Bag-Catching Apparatus, of which the following is a specification.

This invention relates to an improvement 10 in mail bag catching apparatus, and has particular application to apparatus whereby mail bags may be delivered to a moving train.

In carrying out the present invention, it 15 is my purpose to improve and simplify the construction of mail bag catching apparatus of the class described, and to provide apparatus whereby the bag will be automatically gripped as the train passes the station, 20 thereby holding the bag securely in place so that such bag may be removed from the holder by one of the crew of the mail car.

It is also my purpose to provide mail bag catching apparatus which may be readily 25 and conveniently swung from negative to active position and vice versa, which will embody comparatively few parts and these so arranged and correlated as to reduce the possibility of derangement to a minimum.

30 With the above and other objects in view, the invention consists in the construction, combination, and arrangement of parts hereinafter set forth and falling within the scope of the claims.

35 In the accompanying drawings:—

Figure 1 is a top plan view showing my improved mail bag catching apparatus in use.

Fig. 2 is an enlarged fragmentary plan 40 view of the apparatus removed from the car.

Fig. 3 is a bottom plan view of the apparatus.

Fig. 4 is a cross sectional view taken on 45 the line 4—4 of Fig. 2 and,

Fig. 5 is a sectional view taken on the line 5—5 of Fig. 2.

Referring now to the drawing in detail, 1 designates a horizontal cross bar having 50 the ends thereof journaled in an opening formed in the jambs of the doorway of the mail car. Connected to the bar 1 and arranged at right angles thereto is a bar 2. Secured to one end of the bar 2 is a base 55 plate 3, and upstanding from the base plate 3 adjacent the outer edge thereof are pivot

lugs 4. Uprising from the base plate 3 adjacent to one side edge thereof are pivot pins 5 arranged side by side, and pivoted upon the pins 5 are the inner ends of curved gripping jaws 6. The adjacent ends of the jaws 6 are formed with intermeshing toothed segments 7 while interconnecting the jaws adjacent the pivoted lower ends is a coiled contractile spring 8 that acts to hold the 60 jaws normally in gripping position. Pivoted between the lugs 4 is a holding lever 9 having one end formed with a downturned lug 10 and the other end bent downwardly as at 11. Pivoted to the under side of the 65 base plate is a trip lever 12, and one end of the trip lever 12 is connected with the downwardly projecting end 11 of the lever 9 through the medium of a link 13, while the other end portion of the trip lever extends 70 across the space between the jaws 6 below such jaws. 14 designates a leaf spring having one end fastened to the base and the other extremity bearing against the lower edge of the lever 9 to hold the lug end of 75 the lever 9 normally in its lower position.

In practice, when it is desired to use the apparatus, the jaws 6 are swung to open position against the action of the spring 8 and one of the jaws engages behind the lug 80 10 on the lever 9 so that the jaws will be held in open position. The bar 2 is now swung from vertical or negative position to horizontal or active position, so that the apparatus will be in position to catch the bag 85 as the car passes the station, and in the movement of the car the bag strikes the lever 12, thereby swinging the lever 9 against the action of the spring 14 to release the jaws so that the latter may close around 90 the bag under the action of the spring 8 and grip the bag.

It will be understood, of course, that the station may be equipped with apparatus similar to that just described so as to remove 100 the mail bag from the car.

While I have herein shown and described the preferred form of my invention by way of illustration, I desire it to be understood that I do not limit or confine myself to the 105 precise details of construction herein described and delineated, as modification and variation may be made within the scope of the claims and without departing from the spirit of the invention.

I claim:—

1. A mail bag catcher comprising a base

plate, a pair of jaws pivoted upon said base plate and projecting forwardly therefrom, intermeshing segmental gears on said jaws insuring simultaneous movement thereof, a 5 spring connecting and urging said jaws toward each other, a bar pivoted for vertical movement on one side of said plate and having a projection engaging one of said jaws for maintaining said jaws in open position, 10 a spring bearing against said bar and urging said projection to said engaging position, a horizontally movable lever pivoted on the other side of said plate and having one end positioned to be engaged by a mail bag to 15 be caught, and a link connected with said lever and said bar whereby engagement of a mail bag with said lever will swing said bar to disengage said projections for releasing said jaws.

Copies of this patent may be obtained for five cents each, by addressing the "Commissioner of Patents, Washington, D. C."

2. A mail bag catcher comprising a base 20 plate, a pair of jaws pivoted thereon and movable simultaneously, a spring normally urging said jaws into closed position, a bar pivoted on the top of said plate and movable vertically thereon, a projection on the lower 25 side of one end of said bar engageable with one of said jaws for maintaining them in open position, a downturned extension on the other end of said bar, a lever pivoted intermediate its ends on one end in position to 30 be engaged by a mail bag to be caught, and a link connected with the other end of said lever and said downturned extension on said bar whereby movement of said lever will release said jaws.

In testimony whereof I affix my signature.

JOSEPH H. MURRAY.
